(57) CLAIM

The ornamental design for a sofa, as shown and described.

DESCRIPTION

FIG. 1 is a top, front, left side perspective view of a first component of a sofa showing my new design with a second component removed;

FIG. 2 is a bottom, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, left side perspective view of a second component of the sofa, showing my new design in an open configuration, with the first component removed;

FIG. 10 is a bottom, rear, right side perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a top, front, left side perspective view thereof, shown in a closed configuration;

FIG. 18 is a top, front, left side perspective view of the sofa, showing both the first and second components in a first condition of use;

FIG. 19 is a top, front, left side perspective view of the sofa, showing both the first and second components in a second condition of use; and,

FIG. 20 is an enlarged view of detail 20 shown in FIG. 1. The broken lines in the drawings depict portions of the sofa that form no part of the claimed design.

1 Claim, 20 Drawing Sheets
